UNITED STATES PATENT OFFICE.

WALTER C. O'KANE, OF DURHAM, NEW HAMPSHIRE, ASSIGNOR TO THE RED-E COMPANY, OF COLUMBUS, OHIO, A FIRM COMPOSED OF WALTER C. O'KANE AND FRANK M. RAYMUND.

CAMP-STOVE.

1,333,335.

Specification of Letters Patent.

Patented Mar. 9, 1920.

Application filed January 27, 1916. Serial No. 74,696.

To all whom it may concern:

Be it known that I, WALTER C. O'KANE, a citizen of the United States, residing at Durham, in the county of Strafford and State of New Hampshire, have invented a certain new and useful Improvement in Camp-Stoves, of which the following is a specification.

The object of this invention is to provide 10 a camp stove of cheap and simple construction, the parts of which are all connected together to prevent loss of any part but which are foldable to form a compact package convenient for handling, transportation 15 or storage.

The invention is embodied in the construction shown in the accompanying drawing, set forth in the following description and finally claimed.

20 In said drawing—

Figure 1 is a perspective view looking at the open side of the unfolded stove and set up for use.

Fig. 2 is a plan view looking at the upper edge of the folded stove.

Fig. 3 is a detail in section showing another method of hinging the grid to the back.

In the views 5 designates the back, which 30 is made of sheet metal, and is of oblong form with its two vertical edges bent forward to form narrow flanges 6 and 7. Hingedly secured to these flanges are end pieces 8 and 9, also of sheet metal, said 35 pieces each being of the same height as and about half the length of the back.

10 designates the grid which consists of a rectangular outer frame of iron rod subtended transversely by parallel wires. The 40 grid is of nearly the same dimensions as the back or so as to fit within the frame formed by the back and ends when the latter are set up at right angles to each other. The grid is hinged to the back, as shown in Fig. 1,

45 by means of short metallic straps bent so as to form when riveted to the back, as seen at 12, elongated hinge members 11 in which the outer frame of the grid is secured. To support the grid in horizontal 50 position the end walls 8 and 9 are provided with hooks 13 and 14 which receive the ends of the outer frame of the grid when the latter is manipulated for that purpose. When so engaged the end walls are held fixed

to stand at right angles with reference to 55 the back.

In practice the stove should be set up on the ground with the back facing the wind, if any be blowing, and the fire built under the grid within the inclosure formed by the 60 back and ends. To promote draft a small hole can be dug in the ground under the lower edge of the back.

The advantage of the elongated hinge member is that it is possible to locate the 65 grid for cooking purposes somewhat below the upper edges of the walls and closer to the fire without detaching the grid from the back.

In folding the parts, the grid is removed 70 from the hooks and turned down flat on the back. To secure the grid within the compass of the back and folded ends it can be slid upward and supported upon a lug 15 near the lower edge of the inner side of 75 the back. After the grid has been thus folded against the back the ends are folded down on the grid, said ends being secured together in closed position if desired, by a hook 16 on one end and an eye on the 80 other as shown in Fig. 2.

Instead of employing an elongated hinge for the grid as shown in Fig. 1 the grid can be hinged as seen in Fig. 3, somewhat below the upper edge of the back so as not 85 to be slidable on the back as is the case in Fig. 1.

A stove thus constructed can be conveniently transported on pleasure trips and promptly set up anywhere, no spikes or 90 other devices being required to hold the same in erected position. Another advantage is that the fire is protected from the wind on three sides and the heat confined to function on the contents of the grid. 95

Because the parts are all connected together it is impracticable to leave any constituent part behind and lose it. However, in the purview of my invention some parts can be modified without departing from the 100 gist thereof as claimed.

What I claim is:

1. A camp stove comprising, in combination, a back wall, two end walls hinged to the opposite ends of the back wall to 105 fold on the same side of the back wall, said end walls each having a width substantially half that of the back wall, a grid having a

hinge connection with the back wall so as to be foldable thereon and be confined directly by said back wall and end walls when in folded relation and means for supporting 5 the forward portion of the grid in elevated position when the walls are unfolded and erected for use.

2. A camp stove comprising, in combination, a back wall having its ends bent 10 forward to form narrow flanges, end walls hinged to said flanges to fold on the same side of the back wall, a grid and vertically elongated hinging means on the back wall for slidably receiving the rear edge of the 15 grid, whereby the grid may be confined between and within the boundaries of the back and end walls.

3. A camp stove comprising, in combination, a back wall having its ends bent 20 forward to form narrow flanges, end walls hinged to said flanges to fold on the same side of the back wall, a grid, vertically elongated hinging means on the back wall for slidably receiving the rear edge of the 25 grid and means on the end walls for supporting the grid in horizontal position between the end walls.

4. A camp stove comprising, in combination, a back wall having its ends bent 30 forward to form narrow flanges, end walls hinged to said flanges to fold on the same

side of the back wall, a grid, vertically elongated hinging means on the back wall for the rear edge of the grid, means on the 35 end walls for supporting the grid in horizontal position between the end walls, and a stop 15 to prevent the grid from protruding beyond the boundaries of the back wall upon said elongated hinging means when the parts are in folded relation. 40

5. A camp stove comprising, in combination, a back wall having its ends bent forward to form narrow flanges, end walls, each of less than half the length of the back wall hinged to said flanges to fold on 45 the same side of the back wall, a grid, vertically elongated hinging means on the back wall for supporting the rear edge of the grid and means on the end walls for supporting the grid in horizontal position between the 50 end walls.

6. A camp stove comprising, in combination, a back wall, an end wall hinged to each end of the back wall to fold on the same side of the back wall, a grid and 55 vertically elongated hinging means connecting the grid with the back wall whereby the grid may be turned and slid into parallel relation to the back wall and be inclosed by the back and end walls.

WALTER C. O'KANE.
